UNITED STATES PATENT OFFICE.

JOHN W. STOCKETT, OF WASHINGTON, DISTRICT OF COLUMBIA.

FIRING ATTACHMENT FOR BREECH-LOADING ORDNANCE.

SPECIFICATION forming part of Letters Patent No. 699,256, dated May 6, 1902.

Original application filed October 20, 1900, Serial No. 33,761. Divided and this application filed June 3, 1901. Serial No. 62,994. (No model.)

To all whom it may concern:

Be it known that I, JOHN W. STOCKETT, a citizen of the United States, residing at Washington, in the District of Columbia, have invented certain new and useful Improvements in Firing Attachments for Breech-Loading Ordnance, of which the following is a specification.

My invention relates to firing attachments for breech-loading ordnance, and more particularly to that class of breech-loading ordnance in which separate loading for the ammunition is employed—that is, the projectile and its propelling charge are separate.

The object of the invention is to provide a simple, cheap, and effective firing mechanism which is adapted to operate either electrically or frictionally for firing the primer, and to so arrange the parts that they will operate practically and successfully at the desired times, but cannot be operated in such a manner as to cause damage to the gun or danger to the operators.

To these ends my invention consists in the various features of construction and arrangement of parts having the general mode of operation substantially as hereinafter more particularly pointed out.

Referring to the accompanying drawings, Figure 1 is a rear elevation of a portion of a carrier and breech-block having the improved firing attachment applied thereto. Fig. 2 is a longitudinal vertical section on the line 2—2, Fig. 1. Fig. 3 is a front view of the slide. Fig. 4 is a plan view of a housing. Figs. 5, 6, and 7 are respectively plan, rear, and side views of a cylindrical tumbler; and Figs. 8 and 9 are side and rear views of an ejector.

While my attachment can be applied to ordnance of different constructions, I have shown sufficient in the present drawings of a construction to enable those skilled in the art to make and use the invention and have shown it applied to a breech-block in which there is a spindle adapted to support a gas-check pad, and the breech-block is arranged so that it is free to turn about the spindle, while the spindle is held fixed to the block-carrier in a convenient position.

Thus, referring to the drawings, A represents a portion of a carrier on which is mount-

ed the breech-block B, which is fitted to rotate in an opening A' in the carrier, and there is attached to the carrier a key A², by means of a screw A³, which extends into a segmental groove B' in the breech-block and projects into a longitudinal slot C' in the spindle C, which construction permits the rotation or partial rotation of the breech-block on the carrier, but prevents the spindle C from rotating. This spindle C is provided with a passage c, which is enlarged at the outer end, as at c', where it is adapted to receive the primer or firing-tube P. The breech-block is recessed, as at B², and in the present instance is shown as provided with a washer or bearing B³ and another bearing B⁴, between which are placed the balls B⁵, and there is a nut C², engaging the spindle C, and the bearing B⁴ for holding the parts together, so as to permit the breech-block to be rotated about the spindle and on the block-carrier.

Any suitable means for rotating the block may be used, the block in the present instance being shown with an extension B⁶, having a gear B⁷, adapted to engage with a suitable gear for rotating the block.

Mounted on the rear end of the spindle C is a housing D, it being shown as screwed upon the end of the spindle by means of an interrupted screw and as keyed in position by a spline-screw D'. This housing has projecting arms D² D³ and is recessed at D³ to receive the ejector E, and there are slots d, receiving the studs or pins e on the ejector. These studs or pins e are formed integral with the body of the ejector, so that the ejector can be dropped into position in the recess D³ in the housing, and the pins e slip into the inclined slots d, and the ejector is held therein and removed without the necessity of removing a pin or bearing for the ejector, as is usually the case. The ejector is provided at its upper end with a projection e', and its lower end is bifurcated to straddle the primer, and one bifurcation is provided with a lug e², adapted to coöperate with a cylindrical tumbler, hereinafter described.

Mounted in the housing D is a slide F, which has on its inner face a groove F', adapted to be engaged by a pin or stud B⁸, mounted on an extension B⁹ of the breech-block and so

arranged that as the breech-block is rotated to unlock the breech the pin or stud B⁸ causes the slide to move at right angles to the end of the spindle, which movement is preferably 5 at first slow and then quickens, so that the slide is moved in accordance with the shape of the groove F'. A handle F² is also attached to the slide, by means of which it can be raised or lowered manually when desired. The stud 10 or pin B⁸ during this time passes through the vertical portion of the groove F', as best seen in Fig. 3.

Mounted in the slide F are the means for operating the ejector E, and in this instance 15 these means consist of a loose pin or ball G, which is mounted in an oblique slot G'. The arrangement of the parts is such that when the slide is moved upward or away from its normal position the loose pin G comes in contact with the projection e' of the ejector E, which causes its bifurcated end to move outward and throw out the primer or firing-tube P. In order that the ejector E may return to its original position to allow for the insertion 25 of a new or unfired primer, the loose pin G is so mounted in the oblique slot G' that after the pin has tripped or operated the ejector E, as above described, the ejector in turn drops back by gravity to its original position, and in so doing forces the loose pin G 30 out of its way into the upper portion of the oblique slot G'. The loose pin then rolls down the inclined slot G' and rests on top of the projection e' of the ejector E and there remains until the slide F is forced down by the 35 pin or stud B⁸, and during this movement of the slide the loose pin or ball is again forced toward the upper end of the oblique slot G' until it is free to pass around the outer end 40 of the projection e' of the ejector E. Then finally the loose pin by gravity returns to its normal position (shown in Fig. 2) ready to trip the ejector E, so as to eject another primer after the breech has been closed and 45 is ready to open again.

It must be understood that it is necessary to have the ejector return to its original position before the breech-block is closed, as the primer should be inserted while the breech-block is open or in its unlocked position, and 50 in this open or unlocked position the slide F is held up by the stud or pin B⁸ on the breech-block, and it is for this reason that I provide means, as the loose pin or ball, which performs 55 the function of operating the ejector when the slide is moved and which permits both the ejector and the pin or ball to assume their normal positions by gravity after they have performed the function of ejecting the 60 primer.

In order to fire or discharge the primer, I provide means whereby this may be done electrically or frictionally; so that the same construction may be used either with an electric 65 or friction primer, and in the present instance the slide F is provided with an insulated plate H, secured thereto in any suitable manner,

as by screws h h, and separated from the slide by suitable insulation H'. This plate is so arranged that its lower end will normally 70 come in contact with the primer-wire P' and make electric contact therewith, and in the primer shown the wire is provided with a head P², whereby it can be frictionally operated, as hereinafter described. The plate H is provided with a suitable binding-screw and socket H² in the usual manner, by means of which proper electrical connections can be made. The slide F is also provided with means for firing the primer frictionally, as 80 above intimated, and in the present instance I have provided a hinged leaf I, which is pivotally mounted on the slide at its upper end, as by the screw I', and is preferably under stress to keep it in position, and in the present instance I have shown a spring I², surrounding the screw I' and bearing on the slide and on the hinged leaf. As shown, this leaf is slotted or cut away at its upper portion to embrace the binding-screw of the insulated 85 plate H, and the lower end of the leaf is slotted, as at I³, so that it may straddle the primer-wire P' when the slide is down in its operative position and the gun is ready for firing. The leaf is also preferably provided with some 90 suitable means, as an eye I⁴, to which a lanyard or other similar device may be attached for operating the leaf, and when the leaf is so operated its lower portion engages the head or button P² on the rear end of the primer-wire and pulls the primer-wire through its friction composition within the primer, thus 95 igniting the same and firing the gun. It will thus be seen that the same primer-wire is employed to fire the piece, either electrically or by friction at will, and it will further be observed that it will be impossible to fire the gun when the breech-block is in its unlocked position either by the electric current or by the frictional means, as the slide F is then 100 held up and away from the primer-wire by the pin or stud B⁸, so that neither the insulated plate nor the hinged leaf can engage with the primer-wire until the breech is closed and the slide F restored to its normal position. 105

As above intimated, the slide is operated automatically on rotating the breech-block, or it may be operated manually by the handle F² in case, for instance, of misfire or it is desirable to eject the primer without opening 110 the breech of the gun, as this latter would be dangerous for the operator under some circumstances which will be appreciated by those skilled in the art. Moreover, the slide is preferably provided with some sort of means 115 to prevent its being moved entirely out of its housing, especially when operated by the handle, and while any suitable means may be used I have shown a screw d', mounted in the housing D and adapted to engage a slot 120 or recess f' in the side of the slide.

When a fresh primer has been applied, (which is done when the breech-block is open,) in swinging the breech-block to close the

breech there is apt to be a rush of air through the passage or vent c in the spindle, which tends to prematurely eject the unfired primer, and it is desirable to provide means for holding the primer in its seat in the rear end of the spindle when the slide F is raised. To do this, I provide what I have termed a "cylindrical" tumbler K , which in the present instance is mounted on the spline-screw D' and is provided with a slot k , adapted to engage a pin k' on the housing D , which serves to limit the rotation of the tumbler K . This cylindrical tumbler is further provided on its upper surface with two lugs k^2 k^3 . The rear lug k^2 acts to prevent the primer from being forced out of its seat, while the front lug k^3 operates to provide a means for rotating the tumbler and throwing the rear lug k^2 out of the way when it is desired to eject the primer and in the way when it is desired to hold a new or unfired primer in place. When the primer is being inserted, its head comes in contact with the beveled surface k^4 on the front lug k^3 and causes the tumbler to rock to one side, so as to bring the rear lug k^2 in the path of the primer after the head of the primer has passed this lug, thus bringing the rear lug k^2 in such position that it will be in the rear of and overlap the head of the primer and prevent its premature displacement, as shown in Fig. 1. Of course it is necessary to move the rear lug k^2 on the tumbler out of the way before the primer can be ejected, and therefore the lug e^2 on the ejector E is arranged to come in contact with the beveled surface k^5 on the lug k^3 , and this causes the tumbler to rock and throws the lug k^2 out of the way until the primer is ejected. It will thus be seen that the tumbler is rocked into locking position by the act of inserting the primer, and it is also rocked into unlocking position by the operation of the ejector. It will be seen that the lug k^2 is disposed at a short distance from the head of the primer when the same is fully inserted in its seat in the end of the spindle. This is done intentionally, so that the cannoneer will have an abundance of leeway for inserting his primer when the slide is up. If by chance the primer is not fully seated by the cannoneer when the slide is returned to its normal position, the bevel f^2 on the inner face thereof forces the primer completely home.

Having thus described the details of construction and pointed out generally the mode of operation of the parts of my improvement, it will be understood that they may be used separately or in combination with each other, as shown, or in combination with other operating parts, and the details of construction may be varied by those skilled in the art to adapt them for use in connection with different forms of breech-blocks, and I therefore do not limit myself to the precise details of construction shown and described. Some of the features, broadly considered, are shown

in my application, Serial No. 33,761, filed October 20, 1900, but are not claimed therein, this present application being a division of my prior application in so far as the features shown and described therein are embodied in this present case.

What I claim is--

1. The combination with a carrier, of a breech-block mounted thereon, a spindle extending through the breech-block, and means connected to the carrier to permit the breech-block to turn but to prevent the spindle from turning, substantially as described. 75

2. The combination with a carrier, of a breech-block mounted thereon, a spindle within the breech-block, and a key mounted on the carrier, the breech-block and spindle being provided with grooves for the key whereby the breech-block can rotate and the spindle is prevented from rotating, substantially as described. 80

3. The combination with a spindle having a firing-opening for the reception of the primer, of means for holding the primer in position, and an ejector arranged to operate said means, before ejecting the primer, substantially as described. 90

4. The combination with a spindle having a firing-opening for the reception of the primer, of means for retaining the primer in position, an ejector for operating said means and ejecting the primer, and firing mechanism arranged to operate the ejector, substantially as described. 95

5. The combination with a spindle having a firing-opening for the reception of the primer, of means for retaining the primer in position, an ejector arranged to operate said means and eject the primer, a movable firing mechanism, and means connected to said movable firing mechanism for operating the ejector, substantially as described. 100

6. The combination with a spindle having a firing-opening for the reception of the primer, of a tumbler for retaining the primer in position said tumbler being provided with lugs by means of which it is brought into inoperative and operative position by the insertion of the primer into the opening, substantially as described. 110

7. The combination with a spindle having a firing-opening for the reception of the primer, of an ejector, and a slide provided with an oblique slot and a loose pin mounted in the slot and adapted to engage the ejector, substantially as described. 115

8. The combination with a spindle having a firing-opening for the reception of the primer, of a slide having an oblique slot, and a loose pin mounted in said slot and adapted to engage and operate the ejector, substantially as described. 120

9. The combination with a spindle having a firing-opening for the reception of the primer, of an ejector having a projection, a slide having a recess embracing the projection and hav-

- ing an oblique slot, and a loose pin mounted in the slot and adapted to engage said projection to operate the ejector, substantially as described.
- 5 10. The combination with a spindle having a firing - opening for the reception of the primer, of a slide, an insulated plate mounted on the slide and adapted to engage the primer-wire, and a leaf also mounted on the 10 slide adapted to embrace the primer-wire, substantially as described.
11. The combination with a spindle having a firing-opening for the reception of a primer, of a housing mounted on the spindle, a slide 15 movably mounted in the housing; said slide being provided with an oblique slot, a loose pin mounted in the slot, an ejector operated by said pin, and a handle whereby the slide may be manually moved and the ejector op- 20 erated to eject the primer, substantially as described.
12. The combination with a spindle having a firing - opening for the reception of the primer, of a housing mounted on the spindle, 25 an ejector mounted in the housing and having a projection, a slide mounted in the hous- ing having a recess embracing the projection and an oblique slot, and a loose pin mounted in the slot and adapted to engage the projec- 30 tion, substantially as described.
13. The combination with a spindle having a firing - opening for the reception of the primer, of a housing mounted on the spindle, an ejector mounted in the housing and hav- 35 ing a projection, a slide mounted in the hous- ing and having a recess embracing the projec- tion and also having an oblique slot, and a loose pin mounted in said slot and adapted to engage said projection, substantially as de- 40 scribed.
14. The combination with a spindle having a firing - opening for the reception of the primer, of a housing, a slide mounted in said housing, an insulated plate mounted on said 45 slide, a hinged leaf also mounted on said slide, and means for moving the slide into and out of operative position, substantially as de- scribed.
15. The combination with a breech-block 50 having a projection, of a spindle mounted within the breech-block, a housing mounted on the spindle, and a slide mounted in the housing having a groove and adapted to be operated by the projection on the breech-
- block engaging said groove, substantially as 55 described.
16. The combination with a spindle having a firing - opening for the reception of the primer, of a housing mounted on the spindle, means for retaining the primer in position, 60 an ejector mounted in the housing and pro- vided with a lug for operating said retaining means, a slide mounted in the housing, and means for operating the ejector and thereby operating the retaining means and ejecting 65 the primer, substantially as described.
17. The combination with a spindle having a firing - opening for the reception of the primer, of an ejector, a slide, having an oblique slot, and a loose pin mounted in said 70 slot, whereby the ejector is positively oper- ated when the slide is moved in one direction and the ejector and pin resume their normal positions after the primer is ejected, substan- tially as described. 75
18. The combination with a housing having a recess and inclined slots, of an ejector hav- 80 ing integral studs adapted to be slipped into the slots and retain the ejector in the recess, substantially as described.
19. The combination with a gun having a firing-opening for the reception of a primer, of an ejector, and a rocking primer-retainer adapted to engage the outer rear end of the 85 primer, substantially as described.
20. The combination with a gun having a firing-opening for the reception of a primer, of an automatic primer-ejector, and a rocking primer-retainer adapted to engage the outer rear end of the primer and mounted inde- 90 pendently of the ejector, substantially as de- scribed.
21. The combination with a gun having a firing-opening for the reception of a primer, of an automatic primer-ejector, a rocking 95 primer-retainer adapted to engage the outer rear end of the primer and mounted independ- 100 ently of the ejector, and means connected with the ejector for operating the retainer, substantially as described.

In testimony whereof I have signed my name to this specification in the presence of two subscribing witnesses.

JOHN W. STOCKETT.
